FIRE ALARM SWITCH

John H. Derby, Scarsdale, N. Y.

Application August 3, 1937, Serial No. 157,105

4 Claims. (Cl. 200—140)

This invention relates to thermostatic circuit controlling devices of the types which are particularly adapted for use in fire alarm or fire control systems.

5 Thermostatic circuit controlling devices for the aforementioned purposes are of two general types: Those operating upon a rise of temperature above a predetermined maximum and those operating when the temperature rises at a certain rate, the latter type being commonly referred to as rate-of-rise thermostats. Some advantages attach to the use of each of these two types of thermostatic circuit controlling devices, depending upon the place of use. For example, 10 rate-of-rise systems, if not combined with some means for insuring their operation when the temperature reaches a predetermined maximum, do not always detect dangerous increases in temperature, if these increases have been slow or 15 gradual. Furthermore, these systems sometimes give false alarms for sudden increases in temperature which are not associated with dangerous conditions; for example, an up-draft of hot air resulting from the removal of the cover from 20 a kettle of boiling water or the opening of a door between two rooms of markedly different temperatures.

Ideal protection, therefore, usually demands the combination of thermostatic means operating 25 on the rate-of-rise principle with thermostatic means operating when the temperature exceeds a predetermined maximum so that both the quick rise in temperature which is dangerous can be detected and also the more slow but often 30 equally dangerous rise in temperature beyond a predetermined maximum.

An object of the present invention, therefore, 35 is to provide thermostatic circuit controlling means operable both by sudden increases in the temperature of the space protected thereby and also by the rise of the temperature beyond a predetermined safe maximum.

Many thermostatic circuit controlling systems, 40 both those that operate on the rate-of-rise principle and those that operate when the temperature rises above a predetermined maximum are constructed so that they are automatically reset. There are some advantages in this, in that the system is always ready to operate.

45 But automatic resetting also has its disadvantages, particularly where there is no intermediate mechanically or electrically driven signal transmitting means set in operation by the thermostat. If, for example, a fire starts where there is a rate-of-rise system without the intermediate,

independently operated signal transmitting means and the fire smolders without further increase in the room temperature, then the system, after giving an initial alarm, may adjust itself to the constant temperature and cease to 5 give an alarm, leading a distant attendant to believe that there was no fire or that it has been extinguished. Likewise with thermostatic controlling devices operating on the principle of a rise of the temperature above a predetermined 10 maximum, in the absence of intermediate, independently driven signal transmitting means, the falling of the temperature in the neighborhood of the thermostat may not necessarily indicate that the fire has been completely taken 15 care of and yet the thermostat may reset itself and thus fail to continue to give an alarm. It is therefore frequently advisable to provide that the thermostatically actuated circuit controlling means, when operated, remain in operative 20 alarm-sending condition until an inspection of the place from which the alarm was sent has been made.

One of the objects of the present invention is 25 to provide for the maintenance of the operative circuit to the alarm or other signal system, when completed by the action of the thermostat, until the attendant effects the resetting of the controlling means, thus placing upon him the responsibility for having done something to insure himself that there is no further occasion for alarm. 30 At the same time the invention provides for the simple and convenient resetting of the thermostatic circuit controlling means into condition for 35 operation again when the occasion demands.

An important feature of the invention is the 40 utilization of means operating independently of the thermostatic elements but arranged to be actuated thereby for effecting the circuit changing movements of the circuit controlling mechanism whereby reliance upon either the making or maintenance of circuit establishing contacts by the thermostatic elements or by parts moving therewith is unnecessary.

Another important feature of the invention is 45 the arrangement of the parts of the thermostatically actuated circuit controlling mechanism so that they can readily be automatically supervised.

Other objects and important features of the 50 invention will appear from the following description and claims when considered in connection with the accompanying drawings in which a thermostatically actuated circuit controlling device embodying the present invention is illustrated in a preferred embodiment, the drawings for con- 55

venience showing this device in inverted position, that is, with the dome at the top whereas when in use on the ceiling of a room to be protected thereby the dome will extend downward.

5 In the drawings—

Figure 1 is a vertical section through thermostatically actuated circuit controlling means embodying the present invention, the device illustrated in the drawings being shown in inverted 10 position and the section being taken approximately on the line 1—1 of Figure 3 but with the dome and all of the other elements of the device in position except that a part of the dome is shown as broken away;

15 Figure 2 is a sectional detail illustrating the metering vent connected with the air chamber in the dome and also the test vent;

20 Figure 3 is a plan view of the apparatus but with the dome, associated diaphragm and thermostatic elements removed;

25 Figure 4 is a vertical section on the line 4—4 of Figure 3 with the dome, associated diaphragm and thermostatic elements connected therewith, the parts being in position for resetting after operation;

30 Figure 5 is a vertical section on the line 5—5 of Figure 3 with the dome, associated diaphragm and thermostatic elements connected thereto, this view showing the diaphragm in its latched tripping position;

35 Figure 6 is a vertical section on the line 6—6 of Figure 3 with the dome, associated diaphragm and thermostatic elements in position;

40 Figure 7 is a plan view of the rigid and flexible diaphragms looking from the side opposite the dome.

45 In the illustrative embodiment of the invention those parts which might be affected by dust, corrosion, etc., are enclosed within a molded 50 housing 2, of Bakelite or other suitable material, provided with bayonet lock recesses 4 for receiving the cooperating elements 6 of bayonet joints, the elements 6 being carried by an outlet box 8 having on opposite sides nipples 10 provided with any suitable locking means 12 for the cables carrying the transmission wires for the alarm and supervisory circuits. A flanged threaded ring 14, adapted to be screwed upon a threaded portion of the housing or casing 2 of 55 reduced diameter, provides a shoulder 16 which serves to clamp the rolled over flange 18 of the dome 20 between said shoulder and the end of the housing. The ring 14 may be of brass or other suitable material.

60 The dome 20, which is preferably formed of some good heat conducting, not readily corrodible material such as copper, forms with the rigid diaphragm 22 an air chamber for the rate-of-rise thermostat, this air chamber having a central vent 24 through the diaphragm 22 into a smaller air chamber formed between a flexible corrugated diaphragm 26 and the rigid diaphragm 22, the flexible diaphragm 26 being provided at its center with a thickened relatively 65 rigid disk 28 serving as a bearing member for a bearing pin 30 carried by a latch member 32 through which the spring-operated circuit closer is held in open position. To insure tightness of the housing 2 against dust, moisture, etc., a gasket 34 may be provided between the ring 14 and the housing.

70 Expansion of the air in the chamber formed between the dome 20 and the rigid diaphragm 22, which are preferably both made of copper or bronze for heat conducting efficiency, will force

75 a portion of the air through the central vent 24 of this chamber and cause the flexible diaphragm 26 to move its bearing member 28 away from the rigid diaphragm 22, thus causing the latch member 32 to rock about its fulcrum 36.

Also attached to the rigid diaphragm 22 at 38 is a bimetallic thermostat 40 having its free end arranged to bear against a second bearing pin 42 also carried by the latch member 32. It will be noted that both the bearing pin 30 and the bearing pin 42 are threaded through the latch member 32 for adjustment with respect to the respective thermostats and are provided with lock nuts for holding them in adjusted position.

To control the action of the rate-of-rise thermostat, a slow leak is provided between the air chamber within the dome and the interior of the housing 2 so that gradual increases of the temperature of the air in the chamber formed between the dome 20 and the rigid diaphragm 22 20 will drive the excess air out through this leak and thus equalize the pressure on both sides of the flexible diaphragm 26 so that the diaphragm 26 will not be moved away from the rigid diaphragm 22 for gradual temperature changes. 25

It has been found that a metering vent permitting a suitable rate of discharge of the air and intake of air as the temperature varies can be constructed in the following manner:

30 A nipple 44, having a reduced threaded upper end adapted to be screwed into an opening through the rigid diaphragm 22 and to receive a nut 46 for clamping the nipple in position, is provided with a central passage 48 which is enlarged to receive material 50 serving as means 35 for determining the rate of flow of the air. A suitable material for this purpose has been found to be chemically pure lamb's wool. The lamb's wool 50 is preferably clamped between the bottom of the enlarged portion of the passage 48 40 and a disk 52 having a central opening of the desired size, a threaded bushing 54 serving to press the disk 52 against the wool 50 with the desired pressure.

45 To test the rate of flow of the air through the passage 50 there is preferably also connected to the rigid diaphragm 22 a second nipple or tube 56 which may extend through the diaphragm and be provided with a lock nut 58. The tube or nipple 56 provides for the connection of any suitable test apparatus with the interior of the chamber between the dome 20 and the diaphragm 22 to insure proper adjustment of the rate-of-rise defining vent. After the desired test has been made the test tube or nipple 56 will be closed 55 by means of a threaded plug 60 which is then sealed in its closed position to insure air tightness and to prevent tampering therewith.

60 There are preferably provided in this apparatus two circuit closers, one for effecting the closing of the circuit to the central station and the other for effecting the closing of a local circuit. When, for example, the thermostatically actuated circuit controlling device is to be used for indicating fires or dangerous heat conditions in 65 the cabins of a ship, one of the circuit closers may be used to close the circuit to the central station where the alarm is located, and the other may be used to close a circuit to a light near the cabin or group of cabins where the fire is 70 located so that when the one who is to inspect the condition in the cabin or undertake to extinguish the fire comes to the main corridor in which the cabin or group of cabins is located he will at once be advised as to where the cabin or 75

group of cabins is located which has been responsible for the alarm at the central station.

As in most fire alarm systems, it is also important that the various circuits be supervised so that there will be warning at the central station of any broken circuit. Provision is made, therefore, for such connections to the apparatus as will insure proper automatic supervision. A description of the alarm circuit closers or switches necessarily involves also a description of the switches controlling the supervisory circuits.

As hereinabove suggested in order to insure certain and positive operation the invention provides for converting the relatively small movements of the thermostats employed in the present device into positive and forceful circuit closing actions which, so far as the actual circuit effecting contacts are concerned, will be independent of the action of the actuating thermostat after the initial actuation. As herein shown, provision has been made for effecting the closing of the circuits by the release of the stored up force of a spring and also for the maintenance of the circuit closers in their circuit closing position until separate means, under control of the central station, has been actuated to reset the apparatus.

In the illustrative embodiment of the invention, a spring 62, bearing against the under side of one arm 64 of a bellcrank lever and put under tension by said lever when it is in its latched open circuit position shown in Figure 1, provides the stored up power for effecting the circuit closing operation of the two alarm circuit controlling switches provided in the device. The amount of tension in the spring 62 when the parts are in the position shown in Figure 1 may be varied by means of an adjusting screw 66, bearing against the under side of the spring 62.

The arm 64 of the bellcrank lever is connected to two switch members 68 and 70 in such manner that when said bellcrank arm 64 is in the position shown in Figure 1 the resilient switch members 68 and 70 are in position to maintain contact with the lower resilient switch members 72 and 74, respectively, in supervisory circuits. When the bellcrank arm 64 is moved by the spring 62 into the position shown in Figure 5, the switch arms 68 and 70 are then brought into contact with the upper resilient switch members 76 and 78, respectively, of the cabin light circuit and of the central station alarm circuit. The switch members 68 and 70 are insulated from the bellcrank arm 64 and from each other by Bakelite insulators 80 and 82.

Each of the switch arms 68, 70, 72, 74, 76 and 78 is formed of an elongated strip of spring metal such as phosphorbronze, with a suitable contact knob as shown, and is put under tension in both circuit closing positions so as to insure constant pressure at the contacts in either of the positions, that is, either in the position shown in Figure 1, where the switches are maintaining the supervisory circuits, or in the position in Figure 5, where the switches are in their alarm circuit energizing position.

The means for maintaining the supervisory circuit switches in their supervisory circuit closing position, while at the same time maintaining the cabin light and central station alarm switches in their open circuit positions, comprises latch mechanism of which the latch member 32 hereinabove referred to is an element. As shown in the plan view of Figure 3, the arm 64 of the bellcrank lever, which is fulcrumed on a pin or

shaft 86 extending between two ears or lugs 88 and 90 formed on or connected to the Bakelite base 92, is of U-form and a part 84 thereof extends to one side of the bank of switch members 68, 70, 72, 74, 76 and 78. The part of said U 5 most remote from the arm 64 carries an upright portion 94 extending through a slot 96 in the latch member 32 and having a tooth-like formation 98 at its upper end which constitutes 10 the catch for the latch member 32.

As will be seen, the bearing surface of the upright portion 94 of the arm 64 which engages the end of the slot 96 in the latch member 32 is confined to the tooth-like end 98 of said upright portion 94 and therefore only a comparatively 15 slight movement of said latch 32 upward is required to release the bellcrank and permit the action of the spring 62 to rock it about its axis from the position shown in Figure 1 to the position shown in Figure 5. It will be noted that 20 the tooth-like part of the upright 94 is also cut back sharply from its pointed end to provide clearance for the rocking movement of the bellcrank.

To provide for the resetting of the switches and of the latch mechanism which holds them in their reset position, when they have been moved by the spring 62 into their cabin light and alarm circuit energizing positions, means is provided for rocking the bellcrank 64, 84 against the tension of the spring 62 into position to permit the latch member 32 to drop back into latching relation to the upright 94 of the bellcrank. The illustrative means for this purpose comprises an electromagnet 100, mounted at one side of the chamber in the housing 2. The magnet 100, when energized, is arranged to act on an armature 102 fulcrumed at 104 and connected by a link 106 with an upright extension 108 on the bellcrank arm 64 in such manner that when the magnet 100 is energized and pulls the armature 102 toward it the link 106, connected to the upright extension 108 of the bellcrank 64, will rock said bellcrank into the position shown in Figure 1 and permit the latch member 32 to drop into 45 latching relation to the upright arm 94 of the bellcrank, thus resetting the switches into the position shown in Figure 1. Deenergization of the magnet 100, after the resetting operation, leaves 50 the armature 102 free to follow the movements of the bellcrank 64 when the latch member 32 is rocked into its unlatching position.

It will be noted that the metering vent establishes communication between the chamber within the dome 20, which has no other discharge 55 opening, and the chamber in the housing or casting 2, which may or may not have another discharge opening, depending on whether or not it is desirable that it be absolutely air tight. It will be obvious, of course, that the apparatus will 60 operate under either condition, the housing 2 being formed of Bakelite, a relatively poor heat conductor, whereas the dome 20 is formed of copper, a good heat conductor. Thus, while the pressures within the two chambers will be 65 equalized by slow rates of rise of temperature owing to the leakage permitted through the metering vent, when there is a sudden rise of temperature more rapid heating of the air within the chamber in the dome will cause the flexible 70 diaphragm 26 to move the latch member 32 into its switch tripping position.

What I claim as new is:

1. A thermostatically actuated circuit controlling unit comprising, in combination, a cylin- 75

- drical casing having a removable cover and having therein a circuit closer normally impelled toward circuit closing position, a latch for holding said circuit closer in open position, the cover for said casing including a dome, a circular supporting base and a flexible diaphragm together constituting an air chamber, the plane side of said dome being coextensive with the opening to be closed and serving with said base 5 to form a dust tight closure for said casing, said flexible diaphragm being arranged to move said latch into circuit closer releasing position when itself moved by the expansion of the air in said air chamber, and a metering vent through said 10 base into said casing for preventing diaphragm operating expansion of the air chamber air for rates of rise of temperature below a critical rate.
2. A thermostatically actuated circuit controlling unit comprising a housing including a dome formed of heat conducting material and adapted to be exposed to temperature changes in the room to be protected, means including a flexible diaphragm for dividing the interior of said housing into two compartments, a trip 15 switch in the compartment remote from the dome and arranged to be tripped by movement of said flexible diaphragm brought about by expansion of the air in the dome compartment and a metering vent between the two compartments for equalizing the pressure therein when the air expands at less than a critical rate.
3. Thermostatically actuated circuit controlling means comprising, in combination, a circuit closer normally impelled toward circuit closing 20 position, a latch for holding said circuit closer

in open position and a thermostat comprising a movable element so arranged that when it is moved under the appropriate heat conditions it will effect the movement of said latch into circuit closer releasing position, said circuit closer comprising a pair of movable switch members connected to move together, two stationary switch members associated with each movable switch member, whereby each movable switch member may be moved from a position in which it maintains one circuit in closed condition to a position in which it closes another circuit, said latch normally holding said movable switch members in engagement with one pair of said stationary switch members and a spring acting 25 when said latch is released to move said movable switch members into engagement with the other pair of stationary switch members.

4. A thermostatically actuated circuit controlling unit comprising a housing having therein two chambers, one provided with exposed walls of good heat conducting material and the other having its principal walls formed of poor heat conducting material, the separating wall between the two chambers comprising a flexible diaphragm, a trip switch in the compartment partly enclosed by the walls of poor heat conducting material, arranged to be tripped by movement of said flexible diaphragm brought about by expansion of the air in the other compartment, and a metering vent between the two compartments for equalizing the pressure therein when the air expands at less than a critical rate.

JOHN H. DERBY. 35
